UNITED STATES PATENT OFFICE.

RICHARD T. LIGHTFOOT, OF LOS ANGELES, CALIFORNIA.

FILTER.

Application filed March 31, 1920. Serial No. 370,153.

To all whom it may concern:

Be it known that I, RICHARD T. LIGHTFOOT, a citizen of the United States, residing at Los Angeles, in the county of Los Angeles and State of California, have invented a new and useful Filter, of which the following is a specification.

This invention relates to a device for filtering liquids and refers more particularly to a filter which can be readily attached to the domestic faucet so that the water supplied through the faucet will be filtered before being used.

An object of the invention is to make provision for readily securing either filtered or unfiltered water.

Another object is to provide a device of this character which is convenient to use and keep clean.

Another object is to make provision for convenient flushing out of the filter to clean the same.

Another object is to make provision for grinding or rubbing a substantial portion of the surface of the filtering element so as to clean said surface.

Another object is to make provision for easily attaching the filter to a faucet or pipe.

Other objects and advantages will appear in the subjoined detailed description.

The accompanying drawings illustrate the invention:

Figure 1 is a side elevation of the filter, the same being shown attached to a faucet, a portion of the faucet being shown in section for clearness of illustration.

Fig. 2 is an enlarged vertical mid section of the filter shown in Fig. 1.

Fig. 3 is a plan section on line indicated by x^3-x^3 , Fig. 2.

Fig. 4 is a side elevation of the filtering element.

There is provided a passage or chamber of suitable construction, in the drawings said chamber comprising a hollow internally tapered or frusto-conical body 1 and a detachable cup or cover 2 which is screw-threaded at 3 onto the body 1. The smaller end of the body 1 is provided with or forms a nipple 4 which is preferably reduced outwardly and screw-threaded or otherwise roughened as indicated at 5. Fitting tightly on the nipple 4 and securely held thereon by the screw-threads 5 is a resilient bushing 6 constructed of rubber or other suitable material. The normal external diameter of the

bushing 6 is slightly greater than the inside diameter of the spout 7 of the faucet 8 or pipe to which the filter is to be attached so that when the bushing 6 is thrust into the spout 7 the bushing will be compressed to some extent and thus securely hold the chamber 1, 2 in place on the faucet. The bushing 6 seats against a shoulder α on the smaller end of the body 1 and said shoulder is preferably of greater diameter than the bushing so that it will engage the faucet when the filter is attached thereto. It is understood that I do not limit the above described resilient connection to use with the hereinafter described other features of my new filter, since said connection may be used with filters having different features than those now to be described. Resting upon the cover or base 2 is a resilient gasket 9 of rubber or other suitable material, the margin of the gasket being interposed between the larger end of the body 1 and the inner face of the cover 2 so as to make a liquid-proof joint between the body and cover.

Inside of the chamber 1, 2 is a movable filtering element 10 of frusto-conical shape and of such length and diameters as to conform with and fit loosely in the larger end of the body 1, when in its lower position, and to fit tightly in the smaller end of said body, when in its upper position. When the filtering element 10 is in its lower position as in Fig. 2 the bottom face thereof rests upon the gasket 9 which thus serves as a seal to prevent leakage of liquid between the cap 2 and filtering element. It is clear that, when the filtering element 10 is raised from sealing contact with the gasket 9, liquid in the chamber 1, 2 can readily pass between the gasket and the filtering element.

Means are provided for raising and lowering the filtering element 10 so as to move it respectively away from and toward the gasket 9, and such means also include a discharge nozzle whereby the liquid may discharge from the chamber 1, 2 either when the filtering element is spaced from the gasket 9 or when said filtering element is seated upon said gasket and this construction will now be described.

The cover 2 forms a gland 11 of a stuffing box, the cover of the stuffing box being indicated at 12. Extending through the stuffing box is a tubular nozzle 13 provided near its upper end with a port or ports 14 adapted to communicate with the interior

of the chamber 1, 2, when the nozzle 13 is raised to space the filtering element from the gasket 9. The lower end of the nozzle 13 may form or be provided with a disk shaped handle 15 whereby the nozzle may be raised, lowered or turned. The inner end of the nozzle 13 is provided with a screw 16 or its equivalent to engage a cross arm or tongue 17. The ends of the tongue 17 are accommodated in notches 18 which extend radially outwardly from a central recess 19 in the larger end of the filtering element 10 so that rotary and endwise movements of the element 10 is caused by corresponding movements of the nozzle. When the filtering element 10 is in the filtering position shown in Fig. 2 the recess 19 serves as a passage for the liquid that percolates through the filtering element, and since the upper end of the nozzle 13 is open and terminates in the recess 19 it is clear that the liquid thus filtered passes from the recess 19 into the nozzle 13 so as to discharge from the lower end of said nozzle.

To apply the filter to the faucet, all that is necessary is to insert the resilient bushing 6 in the spout 7 and press the same upward until the shoulder *a* comes into contact with the lower end of the spout. This securely fastens the filter in place on the faucet and the attaching of the filter can be effected without employing a plumber for the purpose. In use, if it be desired to obtain filtered water, the water being shut off, the nozzle 13 will be pulled outwardly so as to lower the filtering element 10 into filtering position upon the gasket 9. The faucet handle 20 will then be operated to turn on the water or other liquid and the water will pass through the nipple 4 into the chamber 1, 2. The only outlet for the water, with the filtering element 10 in its filtering position, is through the pores of the filtering element and the water passes through said pores to the recess 19, thence into the nozzle 13 and discharges into whatever vessel is arranged to receive it.

If it be desired to draw unfiltered water from the hydrant, the faucet handle will be operated to shut off the water and the nozzle 13 will then be raised so as to space the filtering element 10 from the gasket 9. Then the faucet handle 20 will be operated to turn the water on and the water will flow into the chamber and between the lower face of the filtering element and gasket and discharge through the ports 14 into the nozzle 13 and from said nozzle into the receptacle placed to receive it.

It is clear that, when the filtering element 10 is seated upon the gasket 9, the pressure of the water tends to hold the filtering element tightly upon the gasket so as to preclude leakage of water between the bottom face of the filtering element and the gasket

9. It is also clear that when the filtering element 10 is in the raised or non-filtering position the water from the faucet will act to wash off whatever accumulations of sediment may have been deposited on the surfaces of the filtering element during the previous filtering operation, and this is one way of cleaning said filtering element. It is understood that if the filtering element 10 is not raised into non-filtering position for any other reason than to clean it, the householder will move it into such position from time to time to effect the washing off of the deposits of sediment from the filtering element.

After the filter has been in service for some time, a certain amount of sediment may be deposited in the pores of the filtering element at the surface of said element and therefore it may be advisable to grind off a small portion of the peripheral face of the filtering element 10 to thoroughly cleanse said face. The grinding operation is effected by pushing upward on the nozzle 13 sufficiently to bring the peripheral face of the filtering element 10 into contact with the inner face of the body 1. Then the operator will turn the nozzle 13 so as to produce friction between the peripheral face of the filtering element 10 and the body 1. This friction is sufficient to rub off peripheral surface particles of the filtering element together with such particles of sediment as have collected in the pores near said surface so that the peripheral surface will be perfectly clean. The operator will then turn the water on so as to wash from the filter chamber the ground off particles of the filtering element and deposits of sediment.

It is understood that the invention is not limited to the exact details of construction shown in the drawings and described above, but that the invention also includes such changes and modifications as lie within the spirit and scope of the appended claims.

I claim:

1. A filter comprising an internally tapered chamber, a filtering element of frustoconical form in the chamber adapted to fit loosely in the larger portion of the chamber when moved toward the larger end thereof and adapted to closely fit the smaller portion of the chamber when moved toward the smaller end thereof, a recess in the larger end of the filtering element, a nozzle having one end in the recess, and means whereby turning of the nozzle will effect turning of the filtering element.

2. A filter comprising an internally tapered chamber, a filtering element of frustoconical form in the chamber adapted to fit loosely in the larger portion of the chamber when moved toward the larger end thereof and adapted to closely fit the smaller portion of the chamber when moved toward the

smaller end thereof, a recess in the larger end of the filtering element, and an endwise movable nozzle having one end in the recess, endwise movement of the nozzle causing shifting of the filtering element.

3. A filter comprising a chamber reduced toward one end and having openings, a filtering element adapted to fit loosely in the larger portion of the chamber when moved 10 toward the larger end thereof and to closely fit the smaller portion of the chamber when moved toward the smaller end thereof, and means to turn the filtering element to cause grinding thereof against the inner surface 15 of the chamber.

4. A filter comprising a chamber reduced toward one end and having openings, a filtering element adapted to fit loosely in the larger portion of the chamber when moved 20 toward the larger end thereof and to closely fit the smaller portion of the chamber when moved toward the smaller end thereof, and a nozzle extending through one of the chamber openings and rotatively engaging the 25 filtering element, said nozzle being rotative.

5. A filter comprising a chamber having openings, one of said openings being at one end of the chamber and a filtering element 30 movable into different positions in the chamber and adapted when moved toward said end of the chamber to form a valve closing the opening in said end, and means to move the filtering element into the different positions.

35 6. A filter comprising a chamber having openings, a filtering element in the chamber provided with a recess, and a nozzle slideable through one of the openings and projecting into the recess and engageable with 40 the wall of the recess.

7. A filter comprising a chamber provided with openings, a gasket surrounding one of the openings, a filtering element in the chamber

ber, and means to move the filtering element into and out of engagement with the gasket. 45

8. In a filter, the combination of a chamber reduced toward one end and having openings, a filtering element in the chamber of smaller size than said chamber adapted to closely fit said reduced end, and means to 50 move the filtering element to and from said reduced end and to turn said element to cause grinding thereof against the inner surface of the chamber.

9. In a filter, the combination of a chamber reduced toward one end and having openings, a filtering element in the chamber of smaller size than said chamber adapted to closely fit said reduced end, and a rotative nozzle extending through one of the 60 chamber openings and rotatably connected with the filtering element.

10. In a filter, the combination of a chamber reduced toward one end and having openings, a filtering element in the chamber 65 of smaller size than said chamber adapted to closely fit said reduced end, and means extending through one of the openings operable to move the filtering element to and from said reduced end. 70

11. In a filter, the combination of a chamber reduced toward one end and having openings, a hollow filtering element in the chamber of smaller size than said chamber adapted to closely fit said reduced end, and 75 a nozzle having one end inserted in the recess of the filtering element and connected therewith and extending through one of the openings of the chamber, said nozzle movable endwise to force the filtering element 80 into contact with said reduced end.

Signed at Los Angeles, California, this 25th day of March, 1920.

RICHARD T. LIGHTFOOT.
